RECESSED DOORWAY UNIT

Gordon Daline, 2446 Park, Minneapolis, Minn.

Filed Jan. 7, 1957, Ser. No. 44,429

Term of patent 14 years

(Cl. D13—1)

Fig 2

Fig. 1 is a front isometric view showing a recessed door unit embodying my new design, the rear being substantially plain and of conventional design and appearance; and, Fig. 2 is a vertical sectional view taken along the entire end in the direction of the arrows 2—2 of Fig. 1.

I claim:

The ornamental design for a recessed doorway unit, substantially as shown and described.
